The ornamental design of a sofa cover, as shown and described.

DESCRIPTION

FIG. 1 is a perspective view of a sofa cover, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is an enlarged view of detail 8 in FIG. 1;

FIG. 9 is an enlarged view of detail 9 in FIG. 1;

FIG. 10 is an enlarged view of detail 10 in FIG. 6; and,

FIG. 11 is an enlarged view of detail 11 in FIG. 6.

Both the short and long dash broken lines represent portions of the sofa cover that form no part of the claimed design.
